GAME BOARD

Charles G. Wickman, 498 Parker St., Manchester, Conn.

Filed Feb. 2, 1965, Ser. No. 83,657

Term of patent 14 years

(Cl. D34—5)

FIG. 1

FIG. 2

FIG. 3 is a partial transverse section view thereof taken along line 3—3 of FIG. 1.

The bottom and side not shown are plain and conventional. The dominant features of my design reside in the portions shown in full lines.

I claim:

The ornamental design for a game board, as shown and described.
